BAUDELOT WATER COOLER

Edward G. Lehman, York, Pa., assignor to York
Ice Machinery Corporation, York, Pa., a cor-
poration of Delaware

Application June 7, 1939, Serial No. 277,943

5 Claims. (Cl. 257—256)

This invention relates to the manufacture of heat exchange plates and particularly plates for trickler coolers of the so-called Baudelot type.

Plates of this type are extensively used in heating and in cooling potable liquids, particularly water and milk in which extremely high standards of sanitation impose correspondingly high standards of finish and ease of cleaning.

Non-corrosive steels are now considered the ideal material, but their use requires the manufacture of precise steel stampings which are welded together to produce the finished plate or "leaf". The die costs are high and the market rather limited, so design of a plate in such a way that identical stampings can be used is a matter of more than usual importance.

The present invention provides a plate composed of two main stampings which are identical and hence can be produced by a single set of dies. Similarly the "in" and "out" connection fittings are identical and are symmetrically attached to respective main stampings. This is advantageous from the standpoint of economy and also because the fittings do not connect through the joint between the two stampings. This permits better and stronger joints to be made.

Finally the number of flow passes in a complete plate or leaf is not dependent on the design of the stampings but is determined by inserts which are welded in place before the two main stampings are assembled with each other and welded. Hence, a single set of dies can produce plates of a given size and configuration which differ from each other in the number of passes, arrangement of passes, or both.

It is even possible to use more than one inlet and more than one outlet and to segregate from each other distinct portions and passes in a single plate, adapted for heat exchange fluids of different temperatures. However, double path plates are known and since the elaboration involves only duplication and mechanical skill in applying the invention present in a single path plate, a simple commercial embodiment has been chosen for illustration and detailed discussion and as the basis of claims, but with the understanding that various specifically different embodiments are possible within the scope of the invention.

In the drawings:

Fig. 1 is a face elevation of a simple plate with one inlet and one outlet connection. Portions are broken out to reduce both the height and width of the view, with the result that the connections appear at first glance to be out of scale with the plate.

Fig. 2 is a right-hand edge view of the plate of Fig. 1 (i. e. looking to the left at Fig. 1).

Fig. 3 is a section in the line 3—3 of Fig. 1.

Fig. 4 is a perspective view of the two main stampings before welding together, each with the corresponding flow connection attached. In this view the stamping to the left is viewed from its external (relief) side and that to the right from the internal (intaglio) side, with the pass-defining inserts in place. Thus the two main stampings which are identical are shown ready for assembly and welding.

Fig. 5 is a perspective view of one of the inserts.

Fig. 6 is a perspective view showing the insert welded in place.

Fig. 7 is a fragmentary vertical section showing the formation of the passes and the seam-welds between them.

The two main plate stampings 11 are identical and hence made in the same dies. They are assembled in such a way that if either stamping 11 were rotated 180° about a horizontal axis at its mid height and in the mating plane it would assume the position of the other stamping. Statements of direction just made refer to Fig. 1.

The median plane of the complete leaf, which is the mating plane on which the main weld is made is the plane of the inner face of the marginal flange 12. Adjacent this flange are two vertical header bosses 13, both struck out from the median plane. Connecting the two header bosses 13 are a plurality of horizontal pass bosses 14, also struck out from the median plane and merging with the headers.

The header bosses 13 are semi-cylindrical and where two plates are assembled form vertical tubular headers circular in cross section (see Fig. 3). The horizontal pass bosses 14 amount really to a series of corrugations, the corrugations of the two stampings contacting on the median plane on successive inner crests, and there seam welded as indicated at 15 (Fig. 7). The welds 15 are in the plane of the main marginal welds 16 which connect the flanges 12.

In forming the main stampings a slot is formed in one header boss near its end, and the metal is pressed to form a flange 17 which with the adjacent portion of the marginal flange 12 forms a socket to receive the end of the flattened flaring fitting 18. Two stay plates 19 are welded into the flattened mouth of the fitting to resist distortion thereof. The fitting is welded to flange 12 and to flange 17 producing a strong tight joint completely outside the median plane of the leaf.

As best shown in Figs. 2 and 3, the fitting 18 is

offset so that the threaded nipple 21, which is welded to it at 22 is centered on the median plane. This is desirable because it permits the connections with the cooler on which the leaf is to be mounted to be in the same vertical plane. Otherwise, the offset is not important.

The flaring form of the fitting 18 is important because it gives good distribution to the several horizontal passes which provide for the first flow 10 across the plate, and similarly provides for smooth flow to the outlet from the last pass. The fact that it enters the header tangentially (see Fig. 3) is also a valuable feature contributing to good distribution.

15 Since the inlet and outlet connections are on the same vertical edge of the plate, an even number of flow paths across the plate and back are needed. Heretofore, this has been provided for in the stamping of the plate. An important feature 20 of the present invention is the use of flow directing means which may be variously located in the headers before the two main stampings are welded. Thus, a single design of stamping can be used to produce plates which are externally identical, but which have different pass arrangements.

The flow directing means takes the form of an insert 23 which serves as a barrier (Figs. 5 and 6). The insert 23 is generally circular to conform to the internal contour of the header. It has 30 small projections 24, 25. These are formed to fit, respectively, the reverse curve leading to the weld 15 (in the plane of one of which welds the insert 23 is mounted), and the slight fillets between flanges 12 and respective header bosses 13.

35 Each insert 23 except along the projections 24, 25, has a flange, 26, 27. Before the stampings 11 are welded together the fittings 18 are welded in place and the inserts 23 are mounted in proper position, each insert being spot welded to a stamping at points in a flange 26 or 27.

Then the two stampings are clamped together in proper relative positions, and the flange welds 16 are made. Next the seam welds 15 are made. The order in which the welds 15 and 16 are made 45 can be varied.

It is unnecessary to weld the second flange 26 or 27 of the inserts 23, but this can be done if desired. It is not necessary that the inserts 23 seal absolutely tightly, and since they can easily 50 be made substantially tight, the extra expense of assuring absolute tightness is usually not justified.

With these inserts 23 located as shown on the right-hand stamping of Fig. 4, four passes would 55 be provided. One insert would give two passes, five inserts would give six passes, and so on.

After the welding operation is completed, the welds are ground and the entire leaf is polished. In use the plate is mounted in a vertical plane 60 with the headers vertical (Fig. 1). A heating or cooling fluid is circulated through the plate entering at one connection 18 and leaving at the other. Volatile refrigerants may be evaporated in, or vapors may be condensed in the leaf, since 65 it is well stayed against distortion by internal or external pressures. The liquid to be cooled or heated is trickled over the plate according to the usual practice with "Baudelot coolers."

The advantages offered by the invention are 70 important. The design is simple, so that the dies are comparatively simple to make. Only one set of dies is required and can produce blanks for exchangers of various pass arrangements. The flow characteristics are good for both the internal fluid and the external liquid. An exceptionally 75

smooth external finish is easily attainable. Mechanical strength is good.

The construction of various specifically different heat exchange leaves according to the invention is contemplated, so that detailed description here given is to be taken as illustrative and not limiting.

What is claimed is:

1. A heat exchange plate comprising two identical sheet metal stampings having peripheral mating flanges welded together, the mating faces of the flanges being in the median plane of the plate, each stamping having two parallel header channel bosses pressed outward from said median plane, and pass channel bosses forming channels connecting the header channels and also pressed outward from said median plane, each stamping having an opening partially bounded by a seat formed in the wall of a header channel, said opening being near the end of the channel and outside but adjacent to said peripheral flange whereby the flange forms the complementary portion of said seat; and flow connection fittings welded to said seats and to said flanges.

2. A heat exchange plate comprising two identical sheet metal stampings having peripheral mating flanges welded together, the mating faces of the flanges being in the median plane of the plate, each stamping having two parallel header channel bosses pressed outward from said median plane, and pass channel bosses forming channels connecting the header channels and also pressed outward from said median plane, each stamping having an opening partially bounded by a seat formed in the wall of a header channel, said opening being near the end of the channel and outside but adjacent to said peripheral flange whereby the flange forms the complementary portion of said seat; and flow connection fittings welded to said seats and to said flanges, the openings being elongated in the direction of the length of the header channels and the fittings being correspondingly flared whereby the flow capacity of the fittings approximates that of the header with which it communicates.

3. A heat exchange plate comprising two identical sheet metal stampings having peripheral mating flanges welded together, the mating faces of the flanges being in the median plane of the plate, each stamping having two parallel header channel bosses pressed outward from the plane of the flanges, and pass channel bosses forming channels connecting the header channels and pressed outward from the median plane, each stamping having an opening surrounded by a seat formed in the wall of a header channel near the end thereof and outside said peripheral flange; flow connection fittings welded to said seats and arranged to direct flow in a direction tangential to said header; and at least one insert welded in a header channel and obstructing the header formed by mating channels in the two stampings whereby at least two successive flow passes formed by pass channels between said flow connection fittings are afforded.

4. A heat exchange plate comprising two identical sheet metal stampings having peripheral mating flanges welded together, the mating faces of the flanges being in the median plane of the plate, each stamping having two parallel header channel bosses pressed outward from the plane of the flanges, and pass channel bosses forming channels connecting the header channels and pressed outward from the median plane, each stamping having an opening surrounded by a seat

- formed in the wall of a header channel near the end thereof and outside said peripheral flange; flow connection fittings welded to said seats and arranged to direct flow in a direction tangential to said header, said seats being elongated in the direction of the length of the header and the fittings being flared in the direction of the length of such seat; and at least one insert welded in a header channel and obstructing the header formed by mating channels in the two stampings whereby at least two successive flow passes through passes formed by pass channels between said flow connection fittings are afforded.
5. A heat exchange plate comprising two identical sheet metal stampings having peripheral mating flanges welded together, the mating faces of the flanges being in the median plane of the plate, each stamping having two parallel header channel bosses pressed outward from the plane of the flanges, and pass channel bosses forming channels connecting the header channels and pressed outward from the median plane, each stamping having an opening surrounded by a seat formed in the wall of a header channel near the end thereof and outside said peripheral flange; flow connection fittings welded to said seats and terminating in circular nipples, said fittings being so offset that the axes of said nipples lie in said median plane; and at least one insert welded in a header channel and obstructing the header formed by mating channels in the two stampings whereby at least two successive flow passes through passes formed by pass channels between said flow connection fittings are afforded.
10. A heat exchange plate comprising two identical sheet metal stampings having peripheral mating flanges welded together, the mating faces of the flanges being in the median plane of the plate, each stamping having two parallel header channel bosses pressed outward from the plane of the flanges, and pass channel bosses forming channels connecting the header channels and pressed outward from the median plane, each stamping having an opening surrounded by a seat formed in the wall of a header channel near the end thereof and outside said peripheral flange; flow connection fittings welded to said seats and terminating in circular nipples, said fittings being so offset that the axes of said nipples lie in said median plane; and at least one insert welded in a header channel and obstructing the header formed by mating channels in the two stampings whereby at least two successive flow passes through passes formed by pass channels between said flow connection fittings are afforded.
15. A heat exchange plate comprising two identical sheet metal stampings having peripheral mating flanges welded together, the mating faces of the flanges being in the median plane of the plate, each stamping having two parallel header channel bosses pressed outward from the plane of the flanges, and pass channel bosses forming channels connecting the header channels and pressed outward from the median plane, each stamping having an opening surrounded by a seat formed in the wall of a header channel near the end thereof and outside said peripheral flange; flow connection fittings welded to said seats and terminating in circular nipples, said fittings being so offset that the axes of said nipples lie in said median plane; and at least one insert welded in a header channel and obstructing the header formed by mating channels in the two stampings whereby at least two successive flow passes through passes formed by pass channels between said flow connection fittings are afforded.
